TENSION DEVICE

William H. Smith, Cornwall, N. Y.

Application March 13, 1934, Serial No. 715,294

2 Claims. (Cl. 74—242.11)

The invention relates to a tension device or tensional arrangement for keeping taut a driving band or belt which is movable laterally upon a cylinder or from one pulley to another as from 5 a live driving pulley around which the band is passed onto an adjacent auxiliary or dead pulley.

More specifically the invention relates to a tension device or tensional arrangement for keeping taut the band in a twister where the band, passed 10 around a live driving pulley and the whorl of a spindle driven by the pulley, is moved laterally by a stop motion from the live pulley onto an adjacent dead pulley for stopping the operation of the spindle.

15 Among the objects of the invention are the following:

To provide a tension device or tensional arrangement which will operate efficiently under conditions where the band is laterally movable as 20 outlined above, and, also, to provide a tension device or tensional arrangement which will possess the following advantages:

One having relatively few parts;

One to which the band may be quickly applied 25 after placing the band around the driving part and part driven by it;

One which will not require any increase in the normal length of the band;

One that will operate freely and not cause 30 undue wear upon the band adapting itself automatically to the different running positions of the band;

One that may be arranged to increase the extent of frictional engagement between the band 35 and driving cylinder or pulley as the belt stretches; and

Under conditions where the tension device is being used in a twister as referred to above, one 40 that will tend to maintain the band in the plane of the whorl on the spindle as the band stretches, and not to unduly increase the angular position of the band on the whorl which would cause wear.

The invention can best be seen and understood 45 by reference to the drawing in which the tension device is shown as applied to the tensioning of bands in a twister to which machine the device is especially applicable.

In the drawing:

Fig. 1 is a side elevation of the twister with 50 the tension device applied thereto, only those parts of the twister being shown as are necessary for a proper understanding of the invention.

Fig. 2 is a plan of the live driving pulley and adjacent dead pulleys with applied bands, all as 55 hereinafter referred to.

Fig. 3 is a front elevation of the tension device; and

Fig. 4 is a section on the line 4—4 of Fig. 3. Referring to the drawing: 1 represents the driving pulley turning in the direction of the arrow 5 thereon. 2, 2 represent the spindles, each having on it a whorl 3. The spindles are turned by bands 4 passed around the driving pulley and around the whorls on the respective spindles, the bands running in the directions of the arrows alongside the 10 bands.

Arranged adjacent the driving pulley are dead pulleys 5, and during the operation of the machine each band is movable laterally off the live pulley on to the adjacent dead pulley. Such lateral displacement of the band is incidental to the operation of a stop motion, not shown, which operates through a guide fork 6 embracing the taut section of the band near the driving pulley to laterally displace the band away from the live 20 pulley in the direction of the dead pulley. This operation is facilitated by a cam or flange 7 on the live pulley which, when the band is displaced by the fork, engages the displaced band as the live pulley is rotated and strips the band from the 25 live pulley and transfers it to the dead pulley, the return of the band from the dead pulley on to the live pulley being simply a reversal of this operation.

Arranged adjacent each of the bands is a tension device 10 borne by a bracket arm 11 suitably fixed to the frame of the machine. The tension device 10 comprises a tension pulley 12 having a grooved rim 13, preferably substantially V-shaped in cross section, over which the band passes. The 35 tension pulley is fast on a shaft 14 which turns in bearings 15 borne by the forked ends of arms 16, 16 of a yoke having a cross bar 17 connecting said arms and which lies parallel with the shaft of the tension pulley. The bearings 15 are held 40 against outward displacement and the ends of the openings through the bearing closed, by ears 18 fixed to the arms of the yoke and overlapping the ends of the respective bearings. The bearings 15 are preferably rather widely separated from one 45 another and elongated in order that the shaft 14 bearing the tension pulley may not only rotate thereon but have longitudinal movement therein, thus affording an appreciable lateral play to the tension pulley during its rotation. Secured to 50 the cross bar 17 of the yoke with outward extension at right angles thereto and to the shaft of the friction pulley is a spindle 20 which extends through and turns within a boss 21 laterally offset from the end of a plate 22. This plate has a lon- 55

5 gitudinal slot 23 in it and the plate is adjustably secured to the bracket arm 11 to extend outwardly therefrom by means of a bolt 24 passed through the slot in the plate and through an 10 opening in the arm and secured by a tightening nut 25 for any adjusted position of the plate. The end of the spindle projecting through and beyond the boss is provided with a head 26 which has drawing engagement with the end of the boss. 15 10 Coiled upon the spindle and tensioned between the yoke and the boss is a spring 27, one end of which bears against the cross arm 17 of the yoke and the other against the boss, a washer 28 being preferably interposed between the end of the 15 spring and the boss.

In a tension device thus provided the tension pulley will exert tensional force for taking up slack in the band passed over it depending upon the amount of compression of the spring 27, and 20 depending, also, upon the outward extension of the plate 22 from the bracket arm 11, in the direction of the band, this depending upon the adjusted position of the plate on the arm.

The tension device is arranged to bring the 25 tension pulley against the slack section of the band as near the driving pulley as possible. The band is applied to the tension pulley simply by retracting the pulley for compressing the spring and then releasing the pulley to bear with tensional force against the band for taking up slack in it, the band then passing over the tension pulley as though it were an idler.

When the tension device is initially applied to the band and the band is new the plate 22 will 30 be fixed to have its minimum extension from the bracket arm to which it is secured and the spring will be compressed in a maximum amount. The band is then applied to the pulley simply by slipping it into the grooved rim of the pulley and the pulley released. Thereupon the turning pulley will tend to form a slight bend in the band. As the band stretches all slack will be taken up as long as the tension pulley remains in a position to bear tensionally against it. When the 35 stretch of the band has become considerable then an adjustment of the plate 22 with relation to the bracket arm will be required for extending the arm and accordingly bringing the pulley nearer the band. The bend in the band occasioned by the engagement of the tension pulley is such as will effect an increased area of frictional contact between the band and the driving pulley preventing slippage and, also, will bring the band into the plane of the whorl, so reducing the angular relation of the band to the 40 whorl preventing wear. In time the band will become stretched in such amount that its tensional section lying between the driving pulley and the whorl on the spindle will lie substantially within the plane of the whorl in which position the band operates with great efficiency and with minimum wear upon it.

When the band is moved laterally from the live pulley onto the adjacent auxiliary or dead pulley the tension pulley will then tend to align 45 itself with the band so that the band will run properly through the groove of the pulley and not tend to engage the opposite sides of the groove which would cause excessive wear. In this connection it would be explained that where a grooved tension pulley is employed to take up slack in a band it is necessary that the pulley lie in true alignment with the band as it passes tangentially onto and off the pulley within the 50 groove in it. If the tension pulley is not in alignment

then the band, not lying true within the groove in the pulley, will extend more or less crosswise of the groove and bear against opposite sides of the groove causing a scraping action as the pulley is rotated on the sides of the 5 band and the band will soon wear out, considering the speed at which the tension pulley is rotated. It may be thought that if the tension pulley were pivotally mounted so as to turn, it would turn automatically as the band was turned, 10 or laterally shifted, and so continue its alignment with the band. It will not do this however in any ordinary combinations of driving and driven pulleys and on which driving pulley the band is shifted laterally for the reason that when 15 the band is shifted, although the pulley is pivotally mounted, it will not turn but remain in its set position (due at least in part to the high rotational speed of the tension pulley tending to hold it in the plane of its rotation), the shifted 20 band then extending through the groove in the pulley at an angle so as to engage the opposite sides of the groove causing the scraping action and wear on the band as before explained. In the present arrangement however the pulley will 25 turn automatically with the band or shift its position as the position of the band is shifted, and this for the following reason.

As the band is laterally displaced by the guide fork 6 it will be brought into the path of the cam 30 or flange 7 on the live pulley which engages the band as the live pulley is rotated and throws it onto the auxiliary or dead pulley with a very quick action. When the cam strikes the band it makes a bend or flexure in it as may be seen 35 by reference to Fig. 2. This bend or flexure tends to shorten the band with relation to the tension device thereby increasing the tensional bearing of the tension pulley against the band and at the same time will cause a slight longitudinal 40 movement of the spindle 20 bearing the tension pulley within the bearing 21 in which it is pivoted. These effects, together with the quick blow struck the band by the cam will overcome the inertia of the tension pulley and will cause it to turn 45 into alignment with that portion of the band coming onto it. This will cause the band to render properly through the groove in the pulley although with a tendency to bear against one side of the groove rather than at the bottom of the 50 groove, but it will obviate any tendency of the band to engage opposite sides of the groove which is the thing to be avoided. While it is not absolutely necessary to provide for a lateral slip or movement of the tension pulley yet it is better to 55 do this so that the pulley will line up not only with that portion of the band coming on to it, but in so far as possible be in the line of that portion of the band passing off the pulley, the band then rendering properly in the bottom of the 60 groove and not against one side. This lateral slip of the pulley is provided for as previously explained. When the band is returned from the auxiliary or dead pulley onto the live pulley, the operation is substantially a reversal of that ex- 65 plained, the tension pulley then returning to its initial position.

Having thus fully described my invention I claim and desire to secure by Letters Patent of the United States:

1. The combination comprising a rotary driving pulley, a driven member, a driving band connecting said driving pulley and driven member, an auxiliary pulley arranged alongside said driving pulley, a tension pulley having a grooved edge 75

- for receiving said driving band and which pulley is arranged to bear against said band for taking up slack therein, means for flexibly mounting said tension pulley whereby it will yieldingly bear
5 with tension against said band and whereby it will, also, turn so that it may be brought into alignment with said band as the position of the band becomes changed laterally with relation to the driving pulley, and means for moving the
10 band laterally from one to the other of said driving and auxiliary pulleys and, at the same time, actuate said band to bring the tension pulley into alignment therewith as the position of the band becomes laterally changed, including a member
15 on said driving pulley adapted and arranged to strike and flex said band when the band is moved into the path of said member.
2. The combination comprising a rotary driving pulley, a driven member, a driving band connecting said driving pulley and driven member, an auxiliary pulley arranged alongside said driv-
- ing pulley, a tension pulley having a grooved edge for receiving said driving band and which pulley is arranged to bear against said band for taking up slack therein, means for flexibly mounting said tension pulley whereby it will yieldingly bear
5 with tension against said band and whereby it will, also, turn pivotally and with permitted lateral slip so that it may be brought into alignment with said band as the position of the band becomes changed laterally with relation to the 10 driving pulley, and means for moving the band laterally from one to the other of said driving and auxiliary pulleys and, at the same time, actuate said band to bring the tension pulley into alignment therewith as the position of the band becomes laterally changed, including a member
15 on said driving pulley adapted and arranged to strike and flex said band when the band is moved into the path of said member.

20 WILLIAM H. SMITH.
